UNITED STATES PATENT OFFICE.

CLARENCE L. THOMPSON, OF PORT WASHINGTON, NEW YORK, ASSIGNOR TO HALE AND KILBURN COMPANY, OF PHILADELPHIA, PENNSYLVANIA, A CORPORATION OF DELAWARE.

CAR-SEAT.

1,216,885.

Specification of Letters Patent. Patented Feb. 20, 1917.

Application filed September 15, 1915. Serial No. 50,722.

To all whom it may concern:

Be it known that I, CLARENCE L. THOMPSON, a citizen of the United States, residing at Port Washington, in the county of 5 Nassau and State of New York, have invented certain new and useful Improvements in Car-Seats, of which the following is a specification.

My invention relates to railway car-seats 10 of the reversible-back type, and comprises a structure having numerous points of novelty and advantage in comparison with the existing types of car-seat. Briefly, it may be stated that my improved construction is adapted to be formed entirely of 15 steel, as to its metallic parts, the structure therefor being much lighter and stronger than seats of malleable or cast iron construction. It also accomplishes the purpose of 20 providing maximum cushion length for the over-all length of the seat, the construction being such as to permit the seat-cushion to extend a greater distance toward the aisle and wall plates than has been possible with 25 other mechanisms in the past, while at the same time the spaces between the ends of the seat-cushion and the adjacent aisle and wall plates, in which the striker-arms usually move, and in which there was always the 30 danger of a passenger's clothing being caught, are done away with. All the mechanism for moving the seat as the back is reversed is located beneath the seat in exceedingly compact form, a novel type of 35 rocker and rocker-operating mechanism being provided, which results in various advantages which will be pointed out herein-after. The rockers, it may be stated, are operated preferably by means of an eccentric or 40 cam mechanism and what may be termed a "collapsing lever" from the back standards, resulting in a short forward-and-back oscillation of the rocker over the cross-rails on 45 which the rocker is supported, the necessary reversal of the seating inclination of the seat being accomplished with a short forward-and-back movement of the seat, insufficient to cause the seat-cushion to project beyond the ends of the aisle and wall plates, in which 50 projected positions the seat-cushion is in the

way of a passenger entering the seat. The arrangement of seat-operating mechanism does away with the necessity for slotting the back-supporting standards, whereby the latter may be strongly and economically made. 55 In my preferred construction, the cross-rails of the seat are made of tubular section and secured to the wall and aisle plates by slipping the ends of the tubes over short stubs or ferrules on the wall and aisle plates, the 60 rails being held in place by means of cotter-pins or the like. By this means, the construction is made much more economical, strong and light than in previous constructions, while the danger of loosening bolts 65 etc. is obviated.

The objects of my invention are the provision of the improved constructional features above briefly referred to and others hereinafter more fully described, which are 70 combined to form my improved devices.

In order that a clearer understanding of my invention may be had, attention is hereby directed to the accompanying drawings, forming part of this application and illustrating certain embodiments of my invention. In these drawings, Figure 1 represents an end elevation of a seat embodying my invention; Fig. 2 is a front elevation of the same; Figs. 3 and 4 are vertical sections 75 taken on lines 3—3 and 4—4 of Fig. 2, respectively; Fig. 5 is a partial plan view of the seat-operating mechanism, certain parts being shown in horizontal section; Fig. 6 is a vertical section taken on line 6—6 of Fig. 80 5; and Fig. 7 is an enlarged horizontal section, showing the connection between a tubular cross-rail and rock-shaft and one of the end-plates.

Referring to the drawings, the cross-rails 90 1, 1, which in my preferred construction are tubular, are secured at their respective ends to the wall-plate 2 and aisle-plate 3, the rails 1 being supported adjacent to their outer ends by means of the pedestal 4, it being understood that a similar pedestal may 95 be provided, if desired, to support the wall end of the cross-rails. The preferred connection of the tubular rails 1 with the wall-and aisle-plates is illustrated in Fig. 7, in 100

which it is seen that short ferrules or stub-shafts 5 are secured to the wall- and aisle-plates and the tubular rails 1 slipped over the same, the cross-rails and stubs being secured together by any simple suitable means, such as the cotter-pins 6. Each short stub or ferrule 5 may be secured to the adjacent plate in any suitable manner, as by securing the same to a flanged collar 7, which is suitably secured to the wall- or aisle-plate. By the provision of tubular rails, I gain both in cheapness and strength in comparison with the solid rails of angular section commonly used, while the use of the ferrules or stub-shafts with cotter-pins provides a connection with the wall- and aisle-plates of a simple and efficient character, which insures the proper alinement of the cross-rails without any difficulty, while at the same time the use of bolts, which are apt to work loose, is done away with. The tubular rails form bearing surfaces for the rockers, as will be hereinafter described.

The seat-cushion 8 is mounted upon the rockers 9, 9, which latter bear upon the tubular rails 1, 1, as stated. The back-cushion 10 is carried by a pair of standards 11, 11, which standards carry rollers, 12, at their lower ends, on the outer sides of the same, these rollers being mounted in the channel-tracks 13. Tracks 13 are the usual curved channel-tracks formed on the inner faces of the aisle- and wall-plates, rollers 12 traveling through the same, in the usual manner, when the back is reversed.

Standards 11 are secured, as by screws 14, to the ends of the back-cushion, and are each formed with an offset portion 15 to enable the standard to clear the end of the seat-cushion. The standard is bent inwardly underneath the seat, as shown at 16, from which point it extends downwardly to its lower end, which is provided with the rollers 12 referred to.

A pivot-pin for operating the rocker mechanism extends a considerable distance lengthwise of the seat from the inner face of each standard, the seat-cushion considerably over-hanging the rocker-operating mechanism at both ends. The desired position of the pivot-pin referred to is preferably arranged by me, by securing a strap 17, bent in box section, to the inner face of the standard, pivot-pin 18 extending inwardly, lengthwise of the seat, from the web or inner face 19 of the box structure 17 referred to. The mechanism for operating the seat is entirely below the same, as stated, and by the arrangement described I am enabled to prolong the seat 8 into close proximity to the standards 11 and the aisle- and wall-plates, practically no space being left between the ends of the seat and the aisle- and wall-plates, except that necessary for the move-

ment of the standard, of thin section, positioned between the end of the seat and the plate, as described.

Each rocker 9 is mounted, as stated, for oscillatory movement upon the tubular cross-rails 1, 1, each rocker being provided with curved bearing flanges 20, 20, resting on tubular rails 1, 1. Curved guides 21, 21, are cut in the lower portion of each rocker, the upper surfaces of which guides coincide with the curved flanges 20, to accommodate the rails 1 as the rocker moves over the same, horns 22, 22, being provided at the outer ends of guides 21, 21, these horns being inwardly directed lengthwise of the rocker. When the standards and the back-cushion are in their right-hand position, referring to Fig. 3, the seat-cushion is supported with its left end elevated slightly, the right-hand rail 1 being under the right-hand or upper edge of flange 20, with horn 22 below the same, while the left-hand rail 1 is at the right or lower end of the flange 20, which rests upon the same. When the position of the back is reversed, the rockers are moved over the rails 1, into the reverse position, with the left-hand rail 1, referring to Fig. 3, above the horn 22 corresponding thereto, the seat-cushion being then inclined in the opposite direction and moved sidewise a short distance corresponding to the opposite positions of rails 1 with respect to guides 21.

The rockers are preferably operated by cam or eccentric movements, as stated. In the drawings, each rocker is provided, at a position intermediate the cross-rails 1, 1, with a ring 23, mounted for rotation between the upper semi-circular flange 24 formed on the rocker, and a curved bearing strap 25 pivoted at 26 to the rocker and adapted to be secured at its opposite end at 27 to the rocker to form the lower bearing therefor. The tubular rock- or eccentric-shaft 28 is secured eccentrically within the outer annulus 23 of each eccentric. The ends of tubular shaft 28 are rotatably supported on stub-shafts or ferrules 28', on the end-plates, similar to stub-shafts 5 to which cross-rails 1 are secured. A lever 29 is secured to tubular shaft 28, adjacent each end of the same, each lever-member 29 being formed with a longitudinally slotted guide-way 30 therein in which the male lever-member 31 is adapted to slide. Sliding member 31 is provided with a lengthwise slot 32, in which the pivot-pin 18 of standard 11 is adapted to move. The side portions of member 29 are slotted, as shown at 33, in alinement with slot 32, to accommodate pivot-pin 18 when member 31 is telescoped within member 29. When the back is reversed from the position shown in Figs. 3 and 4 of the drawings, tubular rock-shaft 28 and eccentric 23 are oscillated, lever-mem-

ber 31 sliding down into lever-member 29 as the standard passes over the center, and being drawn out again as the standard approaches the opposite side of the seat, the 5 inclination of the seat being reversed as described.

In the movement described of the collapsing levers 29—31, the latter travel in slots 34 in the frame of the seat-cushion, these 10 slots conveniently being spaced between the usual transverse slots of the cushion-frame. The spacing of the collapsing levers in line with these spaces or slots is conveniently arranged by having the pivot-pins 18 extend 15 inwardly a considerable distance from the standards 11, as described. The box-section base 17 for pin 18 provides a strong structure for this purpose. By the arrangement described the usual "striker-arm" having 20 a pivot-pin mounted in a slot in standard 11 is eliminated, whereby the length of the seat is increased, as stated. Also by the elimination of the slots in the standards 11, the latter can be made stronger and be manufactured 25 more cheaply and efficiently.

It is obvious that my invention is not strictly limited to the exact details of construction described, my invention being apprehended to be as broad as is indicated by 30 the accompanying claims. The various constructional features and movements described coact to produce the desired advantageous results referred to, but various of the portions of my invention described may be 35 used without the others, in the form described, with advantageous results.

Having now described my invention, what I claim as new therein and desire to secure by Letters Patent is:—

40 1. In a car-seat, the combination of a pair of cross-rails and supports for the same, a reversible back, supporting standards therefor, a seat, rockers supporting said seat and mounted for oscillatory movement on said 45 rails, said rockers each having a circular opening therethrough with a semi-circular upper flange, a curved bearing strap pivoted at one end to the rocker and adapted to be secured to the rocker at its opposite end to 50 form the lower bearing for said opening, said rockers having curved lower bearing surfaces contacting said rails, a rock-shaft parallel to said rails, extending eccentrically through the openings in said rockers, rings 55 secured on said shaft mounted for rotation within said openings, between said upper flanges and straps, and connections between said standard and said rock-shaft such that reversal of said back oscillates said shaft, 60 and thereby moves said rockers over said rails to reverse the seating angle of the seat, substantially as set forth.

2. In a car-seat, the combination of a seat-cushion, having a vertical slot in the frame

thereof, rockers supporting the same, a back-supporting standard, movable past said seat-cushion, and connections between said standard and rockers for operating the latter as the back is reversed, comprising a lever mounted in a vertical plane beneath said 65 cushion, connected to operate said rockers and connected to said standard by a pin and slot connection, the pin of which extends under said seat-cushion, said lever being movable in said slot in the seat-cushion 70 frame, substantially as set forth.

3. In a car-seat, the combination of cross-rails, a support therefor, an end-plate carried by said cross-rails, provided with a track, a reversible back, an end standard 80 therefor extending closely adjacent to said end-plate and having bearing means movably supported on said track, a seat-cushion extending lengthwise into close proximity to said standard, rockers supporting said seat-cushion, supported on said rails, and connections between said standard and rockers for operating the latter as the back is reversed, comprising a pin secured to said standard 85 extending under said seat, lengthwise thereof, a lever pivotally connected to said pin, underneath said cushion, and means operated by said lever for rocking said rockers as the back is reversed, substantially as set forth. 90

4. In a car-seat, the combination of cross-rails, a seat-cushion, rockers supporting the same, resting on said rails, a back-supporting standard, movable past said seat-cushion and having a pivot-pin thereon extending 100 under said seat-cushion, means for moving said rockers, including a shaft parallel to said rails, and means for rocking said shaft comprising a lever secured to said shaft and having a slideway thereon, and a lever 105 slidably mounted in said slideway and having a slot therein, in which said pivot-pin is mounted, substantially as set forth.

5. In a car-seat, the combination of a seat-cushion, having a vertical slot in the frame 110 thereof, rockers supporting the same, a back-supporting standard, movable past said seat-cushion and having a pivot-pin thereon extending under said seat-cushion, a rock-shaft, means for moving said rockers as 115 said shaft oscillates, and means for rocking said rock-shaft, comprising a lever connected to said shaft and pivot-pin, and movable in said slot in the seat-cushion frame, substantially as set forth. 120

6. In a car-seat, the combination of a seat-cushion, having a vertical slot in the frame thereof, rockers supporting the same, a back-supporting standard, movable past said seat-cushion and having a pivot-pin thereon extending under said seat-cushion, a rock-shaft, means for moving said rockers as said 125 shaft oscillates, and means for rocking said

rock-shaft, comprising a lever formed of two portions, one of which telescopes in the other, movable in said slot in the seat-cushion frame, said portions being connected to 5 said pivot-pin and rock-shaft to oscillate the latter by the movement of the former, substantially as set forth.

This specification signed and witnessed this 13th day of September, 1915.

CLARENCE L. THOMPSON.

Corrections in Letters Patent No. 1,216,885.

It is hereby certified that in Letters Patent No. 1,216,885, granted February 20, 1917, upon the application of Clarence L. Thompson, of Port Washington, New York, for an improvement in "Car-Seats," errors appear in the printed specification requiring correction as follows: Page 1, line 17, for the word "therefor" read *therefore*; same page, line 46, for the word "wiah" read *with*; page 3, line 10, for the word "spaced" read *spaces*; same page, line 11, for the word "slots" read *slats*; and that the said Letters Patent should be read with these corrections therein that the same may conform to the record of the case in the Patent Office.

Signed and sealed this 20th day of March, A. D., 1917.

[SEAL.]

F. W. H. CLAY,
Acting Commissioner of Patents.
